US0D1093309S

(12) **United States Design Patent** (10) **Patent No.:** **US D1,093,309 S**
(45) **Date of Patent:** **** Sep. 16, 2025**

(54) **WIRELESS CHARGER**

(71) Applicant: **Zhijun Xiang**, Guangdong (CN)

(72) Inventor: **Zhijun Xiang**, Guangdong (CN)

(**) Term: **15 Years**

(21) Appl. No.: **29/984,279**

(22) Filed: **Jan. 14, 2025**

(30) **Foreign Application Priority Data**

Jan. 8, 2025 (CN) 202530011371.9

(51) **LOC (15) Cl.** **13-02**

(57) **CLAIM**

The ornamental design for a wireless charger as shown and described.

DESCRIPTION

FIG. 1 is a perspective view of a wireless charger showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof, where the wireless charger is shown in a configuration of use.

The broken lines in the drawings depict portions of the wireless charger that form no part of the claimed design.

1 Claim, 9 Drawing Sheets
